Charles Williams

UNITED STATES PATENT OFFICE.

CHARLES WILLIAMS, OF BROOKLYN, NEW YORK, ASSIGNOR TO HIMSELF AND CHARLES J. SHEPARD, OF SAME PLACE.

SIPHONIC RADIATOR.

Specification of Letters Patent No. 20,132, dated April 27, 1858.

To all whom it may concern:

Be it known that I, CHARLES WILLIAMS, of Brooklyn, in the county of Kings and State of New York, have invented, made, 5 and applied to use a new and useful Apparatus for Heating Purposes, which I term a "Siphonic Radiator;" and I do hereby declare that the following is a full, clear, and exact description of the construction and 10 operation of the same, reference being had to the annexed drawing, making part of this specification, wherein—

Figure 1, is a sectional plan of my radiator, and Fig. 2, is a vertical section of the 15 same.

Similar marks of reference denote the same parts.

In the construction of stoves, furnaces and steam and hot water apparatus for heating 20 purposes it is sought to economize space, and at the same time present a large surface to the action of the fire or heat, and also for the radiation of heat to the surrounding air, but said air is generally 25 quiescent, except the slight circulation caused by the radiation to the air immediately in contact with the outside of the apparatus. To induce a circulation of greater force to carry off the heat more rapidly, 30 pipes have been made use of, passing horizontally into the apparatus and then turning up vertically, but in this case considerable difficulty is experienced in fitting such 35 circulating pipes into place, and keeping them in repair.

The nature of my said invention therefore does not consist in the use of circulating hot air pipes in the furnace, but it does consist in the use of an inverted siphon, or what I 40 term a siphonic radiator, composed of a descending and ascending limb so proportioned to each other that the superior force of the air in the ascending limb or limbs shall cause a downward circulation through the 45 descending limb or limbs; and this I accomplish by means of a bent pipe with two vertical limbs of unequal lengths, or by a bent or inverted siphonic pipe having the limbs of an equal or nearly equal length, but

of unequal areas, the circulation being introduced by the superior force of the ascending current in the pipe or limb of the largest area inducing a descending current through the limb of smaller area.

In the drawing I have represented my 55 siphonic radiator in a form which I believe to be best adapted to general use, although the same might be varied so long as the feature of circulation above set forth is maintained.

a, is the lower casing or furnace of any desired size or shape in which the fire is built as at *b*, and the products of combustion conveyed away in any usual manner.

c, is a ring flange joining the furnace 60 casing *a*, to the upper casing *d*, and *e*, is the top or cover to said casing *d*.

f f f are pipes passing down through the ring flange *c*, and connecting through the foot pieces *i*, with the vertical pipes *g*, *g*, *g*. 70 The sectional plan view Fig. 1, shows the manner in which I connect the respective pipes *f* to the pipes *g*, so as to obtain as many pipes as possible in a given space and maintain the circulation as specified.

My apparatus has, among others, the following beneficial features. 1st all expansion and contraction can take place without disturbing the joints. 2nd a powerful circulation is induced to carry off the heat from 80 the apparatus as fast as possible, and the descending and then ascending current of air acts in the most efficient manner to take up the heat. 3rd the circulating pipes can be brought in such close proximity to the 85 fire that the heat is taken from the hottest part in a far more economical manner than can be done where the heat is diffused through an extensive apparatus. 4th the circulation conveys the heat away from the 90 pipes to prevent them burning, whereas if radiation alone were depended on the parts would soon be destroyed by the heat.

I do not claim a hot air chamber or retort, placed in a furnace over the fire and 95 supplied with air by a pipe or pipes placed nearly horizontal, as such has before been used, neither do I claim inducing a down-

ward circulation of the products of combustion as this has heretofore been used both in the flues of chimneys, furnaces, &c., but—

What I claim as my invention and desire

5 to secure by Letters Patent is—

The siphonic circulating and radiating pipes, formed with two or more vertical or nearly vertical limbs, attached at their upper ends to the shell or casing of the furnace

and connected at their lower ends to each 10 other; and operating substantially as and for the purposes specified.

In witness whereof I have hereunto set

my signature this sixth day of July, 1857.

CHARLES WILLIAMS.
